FINGER HAIR WAVE PINCER

Ragnvald G. Leland, New York, N. Y.

Application October 11, 1934, Serial No. 747,957

4 Claims. (Cl. 132—31)

This invention relates to finger wave pincers and has for an object to provide an improved means of waving of hair upon the human head, and more particularly the production of lasting waves, such as are known as finger waves.

A primary object of this invention is to construct a hair pincer which is used in pairs on the fingers making it possible to pinch deeper and sharper ridges in a finger wave using less strength thereby making the wave more attractive and lasting to the patron.

In the present customary manner of making finger waves, the operator finger waves the hair by using the fingers and a comb, and then places a hair net over the patron's head. Next, the operator pinches the hair up in deep ridges before putting the patron underneath a hair dryer to dry out the hair. In pinching up the waves, due to the roundness of the operator's fingers, it is impossible to make deep and lasting waves because there is no sharp or square edge on which to pinch the hair.

With this invention, however, a sharp or square edge is provided on two adjoining fingers so during the pinching operation deep and lasting finger waves in the hair may be easily made.

This invention includes a pair of very inexpensive metal clips or pinchers which are quickly and easily placed on and removed from the operator's fingers.

With the foregoing and other objects in view, as will hereinafter become apparent, this invention comprises the constructions, combinations and arrangements of parts hereinafter set forth, disclosed and shown on the accompanying drawing. In this drawing,

Figure 1 is an elevational view of the finger wave hair pincers or clips applied to a hand,

Figure 2 is a perspective view of one of the hair pincers or clips, and

Figure 3 is a sectional view taken on the line 3—3 of Figure 1.

There is shown at 10 one of the clips forming part of the hair pincers of this invention, this clip 10 being the one that is applied to the forefinger 11 of the operator's hand 12. Another clip 14 is shown as applied to the middle finger 15 of the operator's hand 12. The clips 10 and 14 are substantially identical in outline, but are reversed in angle.

The clip 10 includes an angle bar 16 including a base bar 17 and a side bar 18, bent at right angles to each other, so as to provide a squared edge 19. Integrally extending from the side bar 18 is a curved finger holding portion 20, the width

of this portion 20 being somewhat less than the length of the side bar 18.

The entire clip 10 is made of a thin metal such as tinned iron, or the like and the finger holding portion 20 may be easily bent more or less so as to snugly hold on the finger 11 as clearly shown in Figures 1 and 3.

The complimentary clip or pincer 14 is substantially identical with the clip or pincer 10 in that it includes an angle bar 21 having a base bar 10 22 and a side bar 23 from which extends a finger holding portion 24, the base bar 22 and side bar 23 meeting in a right angular squared edge 25.

As will be apparent, from Figure 3, the angle bars 16 and 21 are identical while the finger holding portions 20 and 24 merely extend in opposite directions so as to encircle the fingers 11 and 12 and hold the pincers or clips in position thereon.

In operation, the pincers or clips are placed on the forefinger and middle finger as shown in Figure 1, so that the squared edges 19 and 25 may be brought into contact with each other at closing the forefinger and middle finger together. Then, when it becomes necessary to pinch the hair during the finger waving operation instead of attempting to pinch the hair with the two naked fingers, the hair is pinched between the side bars 18 and 23 and the squared edges 19 and 25. A deeper and sharper wave is produced thereby while at the same time less strength is needed by the operator in order to produce this more desirable effect.

As will be apparent, these pincers or clips may be made and sold very inexpensively, inasmuch as each of them may be stamped out of a piece of sheet material and then properly folded, the material being substantially the same as that from which tin cans are ordinarily made, if the most inexpensive article is to be produced. More expensive materials may be used however including aluminum, stainless steel, or precious metal.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature of this invention, what is claimed is:

1. Finger wave hair pincers comprising a pair of angle bars, each angle bar of the pair having a finger holding portion integrally extending therefrom.

2. Finger wave hair pincers comprising a pair of angle bars, each angle bar of the pair having a finger holding portion integrally extending therefrom, the finger holding portion on one angle bar extending in an opposite direction to that on the other angle bar.
3. Finger wave hair pincers comprising a pair of angle bars, each angle bar of the pair having a finger holding portion integrally extending therefrom, the finger holding portion on one angle bar extending in an opposite direction to that on the other angle bar, the width of the finger hold-
- 10

ing portion being less than the length of the angle bar.

4. Finger wave hair pincers comprising a pair of angle bars, each angle bar of the pair having a finger holding portion integrally extending therefrom, the finger holding portion on one angle bar extending in an opposite direction to that on the other angle bar, the end of the finger holding portion being curved toward the other bar of the angle bar.
